UNITED STATES PATENT OFFICE.

FRED J. STEIGER, OF TULSA, OKLAHOMA.

DESIGN FOR A HOSIERY EXHIBITOR.

Application filed November 22, 1923. Serial No. 7,850. Term of patent 3½ years.

To all whom it may concern:

Be it known that I, FRED JEROME STEIGER, a citizen of the United States, residing at Tulsa, in the county of Tulsa and State of Oklahoma, have invented a new, original, and ornamental Design for Hosiery Exhibitor, of which the following is a specification, reference being had to the accompanying drawing, forming part thereof.

I claim:

The ornamental design for a hosiery exhibitor, as shown.

FRED J. STEIGER.
